Inventor:

Raymond B. Gilchrist
Atty:- Fred Gerlach his Atty:-

UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed February 25, 1922. Serial No. 539,059.

To all whom it may concern:

Be it known that I, RAYMOND B. GILCHRIST, a citizen of the United States, and a resident of Newark, in the county of Essex and State of New Jersey, have invented certain new and useful Improvements in Drink Mixers, of which the following is a full, clear, and exact description.

The invention relates to drink mixers.

10 In machines for this purpose, the liquid constituents of the drink to be mixed are usually poured into a receptacle which is generally designated a "shaker," from many different containers disposed away 15 from the mixer. The receptacle with these constituents therein is brought to the mixer and placed in operative relation thereto and is removed from the machine after each mixing operation, to discharge its contents. 20 This is rendered necessary, because so many different ingredients and flavors are used in making drinks that they are, in nearly all cases, mixed individually. It is usually necessary to run the agitator for a considerable 25 period to properly blend or mix the constituents and, therefore, it is desirable that provision be made for retaining the receptacle and agitator in operative relation to permit the dispenser to perform other duties 30 during the mixing operation. In drink-mixing, it thus becomes necessary to frequently place the receptacle containing the constituents into cooperative relation to the agitator and to withdraw it from the machine to discharge its contents and cleanse the receptacle between mixing operations.

A desideratum in this art is to expedite and simplify the operations necessary to bring the receptacle and agitator into cooperative relation, to maintain them in such relation, in starting and stopping of the motor and the removal of the receptacle. Heretofore, in machines whereof I am aware which were provided with means to retain 45 the receptacle in cooperative relation to the agitator, it has been necessary in their use to manually manipulate the receptacle into operative position and withdraw it therefrom and to additionally perform some separate step or operation, such as lowering the motor and agitator together, or shifting the agitator and its shaft into the receptacle and relatively to the motor, or raising and locking a receptacle-support to establish and maintain cooperative relation of

the receptacle and agitator or to control the operation of the machine. Another desideratum in this art is to simplify the machine by dispensing with movable connections in and for the driving mechanism for 60 the agitator.

One object is to provide an improved motor-driven drink-mixer having an agitator which is mounted to work or rotate at a substantially fixed point with respect to the 65 motor, with means adapted to receive the receptacle and automatically retain the agitator and receptacle in cooperative relation as a result of the manual manipulation or placement of the receptacle itself. 70

Another object is to provide a mixer of this character with automatic means for controlling the motor responsively to placement and removal of the receptacle.

A further object of the invention is to 75 provide improved means for removably holding a receptacle in cooperative relation with the agitator on a shaft depending from a stationarily supported electric motor.

A still further object is to provide im- 80 proved means for controlling the operation of the motor which drives the agitator.

Another object of the invention is to provide a machine which is simple in construction, which may be easily and readily operated and which is efficient in operation. 85

Other objects of the invention will more fully appear from the following description.

The invention consists in the several novel 90 features hereinafter set forth and more particularly defined by claims at the conclusion hereof.

In the drawings: Fig. 1 is a side elevation of machine embodying the invention. Fig. 95 2 is a front elevation of the receptacle guide. Fig. 3 is a vertical section. Fig. 4 is a section on line 4—4 of Fig. 3. Fig. 5 is a section on line 5—5 of Fig. 3. Fig. 6 is a section on line 6—6 of Fig. 3. 100

The invention is exemplified in a machine comprising an electric motor 10 of usual construction, to the rotor of which is secured a pendant shaft 11 with an agitator 12 fixed to its lower end; a hollow supporting stand 105 comprising a lower portion 13 fixed to a bottom member 14 which is secured to a base 15 by a screw 16, an upper member 17 suitably secured in the member 13, and a bracket 18 suitably secured to the upper end 110

of member 17 to which the motor 10 is suitably secured, as at 19. The electrical connections for supplying energy to the motor 10 comprise a conductor-cord 20 leading through a handle 21 with conductors 22 and 23, connected to the motor and, normally disconnected switch-members 24 and 25 included in the conductor 23 to control the operation of the motor. The casing of the motor 10 is fixedly secured to the support at 19 and the agitator 12 is maintained in substantially relatively fixed vertical relation to the motor.

A receptacle 26 having an open top, a closed bottom 27, a lower wear-band 28 and an upper wear-band 29, is adapted to contain the constituents of the drink to be mixed and to be placed into cooperative relation to the agitator from beneath the latter, which is supported sufficiently above the base 15 and away from the receptacle-support hereinafter set forth to permit the insertion and withdrawal of the receptacle.

The invention contemplates placement of the receptacle into and out of operative relation to the agitator, locking and unlocking the receptacle and control of the motor by manipulation of the receptacle itself, so that shift of the motor or the agitator are not necessary to bring the agitator into working position in the receptacle. For this purpose, a stationary vertically extending receptacle-guide is provided for the back of the receptacle and comprises a lower inclined or upwardly and backwardly sloping member or portion 30 and a vertical upper portion 31 with a supporting-ledge 32 between them. The guide has its front face curved or arcuate in substantial conformity with the outer periphery of the receptacle so that when the latter is pressed backwardly against the guide, the receptacle will be guided against lateral movement and into its operative position without danger of striking the agitator 12.

The receptacle is adapted to be removably and securely held in operative position by the ledge 32 which has an inclined rearwardly and downwardly extending surface 32' to deflect the lower portion of the receptacle backwardly against the front face of the guide-member 31 and hook 33 which is adapted, in conjunction with said member, to hold the upper portion of the receptacle against lateral movement in any direction, being extended into the receptacle to engage its inner-periphery for this purpose. By causing the abutment or holding member 33 to confine the upper and rear portion of the receptacle, the weight of the front portion of the receptacle and the material therein will tend to hold the lower portion of the receptacle in its seat on ledge 32 and against guide-member 31. Hook 33 is secured by screws 33' to a strip 13^a and guide

31 is provided with lugs 31^a which are also secured to strip 13^a. The latter is secured to the supporting standard by screws 13^b.

For the purpose of automatically controlling the operation of the motor by manipulation of the receptacle, a switch-lever 34 has its lower end 35 formed to pivotally fit in the lower end of the standard-member 13 and on the plate 14, is extended through a slot 36 in front of the supporting-standard and through a slot 37 formed in guide-member 31 and is provided with a camportion 38 which is adapted to be struck by the receptacle 26 while it is being raised into operative position and to be held in shifted position as long as the receptacle remains in its operative position. A stop-shoulder 34' is provided on lever 34 to limit the forward movement of the lever under the influence of spring 43, so it will be normally projected into the path of the receptacle the correct distance to operate the motor-switch. Lever 34 is also formed with a cam 39 in the hollow standard, to shift and control a plunger 40 which is slidably held in the hollow-standard and carries a switch-pin 41 at its upper end which is adapted to bridge the gap between the normally separated switch-members 24 and 25 and close the circuit for the operation of motor 10. Switch-members 24 and 25 are secured to a block 42 of insulating material. Plunger 40 may be formed of insulating material, such as wood, and is normally pressed downwardly by a spring 43 interposed between a shoulder on the plunger and a plate of insulating material 44 suitably held in the upper end of the standard-member 17. A wear-plate 45 is secured to the lower end of plunger 40.

The operation of the machine will be as follows: Assuming the parts to be in normal position shown in Fig. 1, the operator will place receptacle 26 containing the constituents of the drink to be mixed, against inclined guide-member 30 and under the agitator 12 as shown by dotted lines in Fig. 1, press it rearwardly with sufficient force to cause the guide to laterally control its vertical movement, and then lift it. In this manipulation, the receptacle will slide on the front-face of the receptacle-guide. After the receptacle leaves the inclined guide-member 30, it will bear against the vertical guide-member 31 and be raised until its upper margin passes into the hook 33 and the lower rim of the receptacle is lifted above ledge 32. When the receptacle is released, its lower rim will pass into the seat on the shelf 32 and the receptacle will be automatically locked in its cooperative relation to the agitator. In its upward movement, the receptacle will engage the cam 38 and rock lever 34 about its lower end so that the cam 39 will raise the plunger 40,

cause the pin 41 to bridge the switch-members 24, 25 and close the circuit for the operation of the motor 10 and cause it to drive the agitator. This occurs preferably before the receptacle reaches its operative position so that the agitator will be rotating and bore its way through any hard material, such as ice cream, as the receptacle is being lifted. The hook or holder 33 positively holds the upper portion of the receptacle, so that it will not be displaced by the forward pressure of the switch lever 34 which is under the influence of spring 43 which tends to hold the switch-lever normally in the position shown in Fig. 2 and to hold the receptacle. When the motor has run for the desired period and the mixing operation has been completed, the operator will raise the receptacle 26 sufficiently to cause it to clear the inclined surface 32^a of ledge 32 and tilt the lower portion of the receptacle forwardly a short distance to cause its lower back portion to clear, and be released from the ledge. Thereafter, the operator will lower the receptacle and press it backwardly sufficiently so that the receptacle will follow the path controlled by guide-members 31 and 32. The wear-band 29 is of sufficient height to prevent its lower edge from catching on ledge 32 while the receptacle is being lowered. When the receptacle has been lowered sufficiently to clear the agitator 12, it will be withdrawn forwardly away from guide-member 30. During the lowering of the receptacle, the switch-lever 34 will pass into its normal position to release plunger 40 and cause it to break the circuit and stop the motor. This occurs, preferably, after the vessel has been lowered sufficiently to bring the liquid therein below the agitator so the latter will run for a sufficient period to discharge the adherent liquid by centrifugal force into the receptacle.

In the drink-mixers comprising an electric-motor with an agitator attached to its rotor, a high speed, usually ranging from 5,000 to 14,000 revolutions per minute, is attained, and when a receptacle or container which is substantially circular in cross-section, as illustrated in the drawings, is used, the agitator, if operating concentrically in the receptacle, will rotate the entire contents or liquid in the receptacle at a high speed and produce a vortex in the material. By retarding the rotation of the contents to cause greater relative rotation of the agitator and the material, the mixing efficiency is increased. In practice it has been found that this can be accomplished by operating the agitator eccentrically in the receptacle, as shown in Figs. 1 and 3. During withdrawal of the receptacle it is lowered obliquely with respect to the axis of the agitator, so that the latter will pass into or nearly into concentric relation to the receptacle and then produce or increase the vortex. This is of advantage, because during the withdrawal of the receptacle, the vortex will cause the liquid to clear the agitator sufficiently early to cause the agitator to centrifugally cleanse itself by discharging the adherent particles into the receptacle before the latter is completely withdrawn.

The axis of the receptacle while it is in its operative position, is disposed between the agitator and the supporting column. A characteristic advantage of this arrangement is that it provides additional clearance for the receptacle in its placement into and its removal from its operative position.

The invention exemplifies a motor-driven drink-mixer with an agitator carried in substantially fixed relation to the motor; in which manual manipulation of the receptacle itself, results in bringing it and the agitator into and in automatically retaining them, in cooperative relation; in which manual manipulation of the receptacle itself results in automatically retaining it and the agitator in cooperative relation and in automatically controlling the motor; in which the receptacle-holding means and the agitator are normally and co-relatively positioned with clearance to permit the receptacle to be readily placed into and withdrawn from its operative position; in which placement and securing of the receptacle in its holding-means are accomplished by manually shifting the receptacle itself backwardly and upwardly around the agitator to its point of deposit, in which the motor and agitator are stationarily mounted and the receptacle-holding means is disposed entirely at the rear of the agitator to provide receptacle-clearance between the support and the agitator; in which a substantially stationary receptacle-support is used with a stationarily mounted agitator; in which the switch for the motor is receptacle-controlled and closed in advance of the time when the receptacle passes into its fixed operative position; in which said switch is opened after the receptacle has been partly lowered from its fixed position; in which the receptacle is well guided in its placement and removal; in which the agitator operates eccentrically while the receptacle is retained and concentrically during its withdrawal; in which the receptacle holding means is simple in construction; and by which the steps to be performed by the dispenser are simplified and reduced to the minimum and the service expedited and improved.

It is to be understood that the novel features may be separately used without including the others, in accordance with the appended claims.

The invention is not to be understood as restricted to the details set forth, since these may be modified within the scope of the

appended claims, without departing from the spirit and scope of the invention.

Having thus described the invention, what I claim as new and desire to secure by Letters Patent, is:

1. In a machine of the character described, the combination of a motor, an agitator driven by the motor and supported from above, means to support the motor, a guide 10 for directing a receptacle while it is being moved by hand into operative position around the agitator, and means for securing the receptacle in its such position.

2. In a machine of the character described, 15 the combination of a motor, an agitator driven by the motor and supported from above, means to support the motor, a stationary guide for directing a manually supported receptacle into and out of operative position around the agitator, and means for 20 securing the receptacle in operative position.

3. In a machine of the character described, 25 the combination of a motor, an agitator driven by the motor and supported from above, means to support the motor, a guide for directing a receptacle while it is being moved by hand into operative position around the agitator, and means for retaining 30 the receptacle in its operative position when it is released by the operator.

4. In a machine of the character described, 35 the combination of a motor, an agitator driven by the motor and supported from above, means to support the motor, a guide for directing a receptacle while it is being moved by hand into operative position around the agitator, means for controlling the motor operated by the manual shift of the receptacle, and means for securing the 40 receptacle in operative position and to cause the controlling means to keep the motor running while the receptacle is in its operative position.

5. In a machine of the character described, 45 the combination of a motor, an agitator driven by the motor and supported from above, means to support the motor, a stationary guide formed for sliding contact with a receptacle while it is being moved by hand 50 to direct it into operative position around the agitator, and means for securing the receptacle in operative position.

6. In a machine of the character described, 55 the combination of a motor, an agitator driven thereby and supported from above, means to support the motor with sufficient clearance beneath the agitator to permit a receptacle with an open top to be raised into operative position around the agitator from 60 below, and a guide disposed at one side of the receptacle to guide the same while it is being manually shifted into operative position around the agitator.

7. In a machine of the character described, 65 the combination of a motor, an agitator

driven thereby and supported from above, means to support the motor with sufficient clearance beneath the agitator to permit a receptacle with an open top to be raised into operative position around the agitator from below, and a guide disposed at one side of the receptacle to guide the same while it is being manually shifted into operative position around the agitator, the guide being formed to permit the operator to grasp the receptacle while it is being shifted into and out of operative position.

8. In a machine of the character described, 70 the combination of a motor, an agitator driven thereby and supported from above, means to support the motor with sufficient clearance beneath the agitator to permit a receptacle with an open top to be raised into operative position around the agitator from below, a stationary guide for directing one side of the receptacle while it is being manually gripped and shifted into and out of operative position comprising a substantially vertical upper portion and a rearwardly and upwardly sloping lower portion, and means to secure the receptacle in operative position.

9. In a machine of the character described, 75 the combination of a motor, an agitator driven thereby and supported from above, means to support the motor with sufficient clearance beneath the agitator to permit a receptacle with an open top to be raised into operative position around the agitator from below, a guide for directing the receptacle while it is being manually gripped and shifted into and out of operative position and with which the receptacle will slidably contact, formed to hold the receptacle against lateral displacement while it is pressed against it, and means for securing the receptacle in operative position.

10. In a machine of the character described, 80 the combination of a motor, an agitator driven thereby and supported from above, means to support the motor with sufficient clearance beneath the agitator to permit a receptacle with an open top to be raised into operative position around the agitator from below, a guide for directing the receptacle while it is being manually gripped and shifted into and out of operative position and with which the receptacle will slidably contact, formed to hold the receptacle against lateral displacement while it is pressed against it, and means controlled by the movement of the receptacle for securing the receptacle in such position.

11. In a machine of the character described, 85 the combination of a motor, an agitator driven thereby and supported from above, means to support the motor with sufficient clearance beneath the agitator to permit a receptacle with an open top to be raised into operative position around the agitator

- from below, a guide for directing the receptacle while it is being manually gripped and shifted into and out of operative position and with which the receptacle will slid- 5 ably contact, formed to hold the receptacle against lateral displacement while it is pressed against it, and means for controlling the operation of the motor operated by the manual shift of the receptacle.
- 10 12. In a machine of the character de- scribed, the combination of a motor, an agi- tator driven thereby and supported from above, means to support the motor with suf- ficient clearance beneath the agitator to per- 15 mit a receptacle with an open top to be raised into operative position around the agi- tator from below, and means for retaining the receptacle upon its manual shift into said position.
- 20 13. In a machine of the character de- scribed, the combination of a motor, an agi- tator driven thereby and mounted in fixed relation to the motor, means to stationarily support the motor so there will be sufficient 25 clearance beneath the agitator to permit a receptacle with an open top to be raised from below into operative position around the agi- tator, and a stationary support for holding the receptacle in operative position around 30 the agitator and on which it may be placed by manual shift thereof into such position.
14. In a machine of the character de- scribed, the combination of a motor, an agi- 35 tator driven thereby and mounted in fixed relation to the motor, means to stationarily support the motor so there will be sufficient clearance beneath the agitator to permit a receptacle with an open top to be raised from below into operative position around 40 the agitator, a stationary support for hold- ing the receptacle in operative position around the agitator and on which it may be placed by manual shift thereof, and means operated by placement of the receptacle into 45 and out of operative position on said sup- port for controlling the operation of the motor.
15. In a machine of the character de- scribed, the combination of a motor, an agi- 50 tator driven thereby and mounted in fixed relation to the motor, means to stationarily support the motor so there will be sufficient clearance beneath the agitator to permit a receptacle with an open top to be raised 55 from below into operative position around the agitator, a stationary ledge for support- ing the receptacle in operative position, and means extending into the upper portion of the receptacle and adapted to engage the in- 60 ner periphery thereof to hold the receptacle on said support.
16. In a machine of the character de- scribed, the combination of a motor, an agi- 65 tator driven thereby and supported from above, means to support the motor so there
- will be sufficient clearance below the agita- tor to permit a receptacle with an open top to be raised into operative position around the agitator, and means for retaining the receptacle in operative position around the 70 agitator comprising an element extending into the upper portion of the receptacle and adapted to engage the inner periphery thereof.
17. In a machine of the character de- scribed, the combination of a motor, an agi- tator driven thereby and supported from above, means to support the motor so there will be sufficient clearance below the agita- tor to permit a receptacle with an open top to be raised into operative position around the agitator, means for retaining the recep- 80 tacle in operative position around the agita- tor comprising an element extending into the upper portion of the receptacle and adapted to engage the inner periphery there- 85 of, and a coacting support for the bottom of the receptacle.
18. In a machine of the character de- scribed, the combination of a motor, an agi- 90 tator driven thereby and supported from above, means to support the motor so there will be sufficient clearance below the agita- tor to permit a receptacle with an open top to be raised into operative position around the agitator, means for retaining the recep- 95 tacle in operative position around the agita- tor comprising an element extending into the upper portion of the receptacle and adapted to engage the inner periphery there- 100 of, means to support the receptacle verti- cally, and a spring-pressed element engaging the receptacle.
19. In a machine of the character de- scribed, the combination of a motor, an agi- 105 tator driven thereby and supported from above, means to support the motor so there will be sufficient clearance beneath the agi- tator to permit a receptacle with an open top to be raised into operative position around the agitator, means for retaining the recep- 110 tacle in operative position around the agita- tor, and means for controlling the opera- 115 tion of the motor comprising an element engaged by the outside of the receptacle while it is being manually shifted into and out of operative position.
20. In a machine of the character de- scribed, the combination of a motor, an agi- 120 tator driven thereby and supported from above, means to support the motor so there will be sufficient clearance beneath the agi- tator to permit a receptacle with an open top to be raised into operative position around the agitator, means for retaining the recep- 125 tacle in operative position around the agita- tor, and means for controlling the opera- tion of the motor comprising a lever dis- posed to be engaged and shifted by the outside of the receptacle while it is manu-

ally held and shifted into and out of operative position.

21. In a machine of the character described, the combination of a motor, an agitator driven thereby and supported from above, means to support the motor with sufficient clearance beneath the agitator to permit a receptacle with an open top to be raised into operative position around the agitator from below, and means adapted to automatically lock the receptacle when it has been manually shifted into such position.

22. In a machine of the character described, the combination of a motor, an agitator driven thereby and supported from above, means to support the motor with sufficient clearance beneath the agitator to permit a receptacle with an open top to be raised into operative position around the agitator from below, and means adapted to automatically lock the receptacle in operative position when it has been manually shifted, the receptacle being releasable from said locking means by manual manipulation thereof.

23. In a machine of the character described, the combination of a motor, an agitator driven thereby and supported from above, means to support the motor with sufficient clearance beneath the agitator to permit a receptacle with an open top to be raised into operative position around the agitator from below, and means to engage the upper and lower portions of the receptacle and hold it in operative position, the receptacle being releasable by manual manipulation thereof.

24. In a machine of the character described, the combination of a motor, an agitator driven thereby and supported from above, means to support the motor with sufficient clearance beneath the agitator to permit a receptacle with an open top to be raised into operative position around the agitator from below, and means for retaining the receptacle in operative position, comprising an element extending into the upper portion thereof, said means permitting the receptacle to be released by its own manipulation.

25. In a machine of the character described, the combination of a motor, an agitator driven thereby and supported from above, means to support the motor with sufficient clearance beneath the agitator to permit a receptacle with an open top to be raised into operative position around the agitator from below, and means for locking the receptacle in operative position comprising members on the inner and outer sides of the receptacle.

26. In a machine of the character described, the combination of a motor, an agitator driven thereby and supported from

above, means to support the motor with sufficient clearance beneath the agitator to permit a receptacle with an open top to be raised into operative position around the agitator from below, and means for retaining the receptacle in operative position comprising members on the inner and outer sides thereof, from which the receptacle can be released by its own manipulation.

27. In a machine of the character described, the combination of a motor, an agitator driven thereby and supported from above, means to support the motor with sufficient clearance beneath the agitator to permit a receptacle with an open top to be raised into operative position around the agitator from below, means for holding the receptacle in operative position comprising members on the inner and outer sides of the receptacle, and means to press one of said members against the receptacle.

28. In a machine of the character described, the combination of a motor, an agitator driven thereby and supported from above, means to support the motor with sufficient clearance beneath the agitator to permit a receptacle with an open top to be raised into operative position around the agitator from below, and means to secure the receptacle in its operative position comprising a holder for one side of the upper portion of the receptacle and a support at the same side provided with means to hold the receptacle thereon.

29. In a machine of the character described, the combination of a motor, an agitator driven by the motor and supported from above, means to support the motor with sufficient clearance beneath the agitator to permit a receptacle with an open top to be raised into operative position around the agitator, means to retain the receptacle in operative position when it has been manually shifted into such position, and means for controlling the motor operated by the manual shift of the receptacle to and from its operative position.

30. In a machine of the character described, the combination of a motor, an agitator driven by the motor and supported from above, means to support the motor with sufficient clearance beneath the agitator to permit a receptacle with an open top to be raised into operative position around the agitator, means to secure the receptacle in operative position, and means for controlling the operation of the motor comprising an element shifted by the receptacle.

31. In a machine of the character described, the combination of a motor, an agitator driven by the motor and supported from above, means to support the motor with sufficient clearance beneath the agitator to permit a receptacle with an open top to be raised into operative position around the

agitator from below, means to retain the receptacle in operative position when it is has been manually shifted into such position, and means for controlling the operation of 5 the motor operated by manual shift of the receptacle to and from its operative position and held to keep the motor running by the receptacle.

32. In a machine of the character described, 10 the combination of a motor, an agitator driven by the motor and supported from above, means to support the motor with sufficient clearance beneath the agitator to permit a receptacle with an open top to be raised into operative position around the agitator from below, means to retain the receptacle in operative position when it has been manually shifted into such position, and means for controlling the operation of 15 the motor, comprising an element shifted by the receptacle and held thereby while the receptacle is held by the retaining means.

33. In a machine of the character described, 20 the combination of a motor, an agitator driven by the motor and supported from above, means to support the motor with sufficient clearance beneath the agitator to permit a receptacle with an open top to be raised into operative position around the agitator from below, means to automatically 25 lock the receptacle in operative position when it has been manually shifted into such position, and means for controlling the operation of the motor comprising an element 30 engaged by the receptacle while it is being manually shifted to its operative position.

34. In a machine of the character described, 35 the combination of a motor, an agitator driven by the motor and supported from above, means to support the motor with sufficient clearance beneath the agitator to permit a receptacle with an open top to be raised into operative position around the agitator from below, means to automatically 40 lock the receptacle in operative position when it has been manually shifted to such position, and means for controlling the motor operated by the manual shift of the receptacle to and from its operative position, 45 the receptacle being releasable by manual manipulation thereof.

35. In a machine of the character described, 50 the combination of a motor, an agitator driven by the motor and supported from above, means to support the motor with sufficient clearance beneath the agitator to permit a receptacle with an open top to be raised into operative position around the agitator, means for holding the receptacle 55 in operative position so that the agitator will be eccentrically disposed in the receptacle while it is in said position, and means for shifting the receptacle transversely during its removal to bring the agitator substantially concentric in the receptacle.

36. In a machine of the character described, 60 the combination of a stationary motor, an agitator driven by the motor and supported from above and maintained in fixed relation to the motor, means to support 70 the motor with sufficient clearance beneath the agitator to permit a receptacle with an open top to be raised into operative position around the agitator, means for securing the receptacle in operative position with the agitator eccentrically disposed in the receptacle 75 while the agitator and receptacle are in operative position, and means for directing the receptacle transversely while it is manually supported and being withdrawn to 80 bring the agitator substantially concentric in the receptacle.

37. The combination with a receptacle having an open top and provided with a wear-band on the outer side thereof, of a 85 motor, an agitator driven thereby and supported from above, means to support the motor with sufficient clearance beneath the agitator to permit a receptacle with an open top to be raised into operative position 90 around the agitator from below, and a guide for the receptacle while it is being manually shifted, formed to be engaged by said band.

38. The combination with a receptacle having an open top and provided with wear- 95 bands on the outer side and adjacent the top and bottom thereof, of a motor, an agitator driven thereby and supported from above, means to support the motor with sufficient clearance beneath the agitator to 100 permit a receptacle with an open top to be raised into operative position around the agitator from below, a guide for the receptacle while it is being manually shifted, formed to be engaged by said bands. 105

39. In a machine of the character described, 110 the combination with an agitator, a motor for driving the agitator, of means for removably supporting the receptacle in its operative position comprising means for engaging the upper end of the container to hold it laterally and means to engage the bottom thereof, and means for controlling the motor operable by placement of the receptacle into the supporting-means. 115

40. In a machine of the character described, 120 the combination of a support, an electric motor mounted on said support, an agitator mounted to rotate in a position substantially fixed with respect to the motor, and means to automatically retain the receptacle in its cooperative relation with the agitator, upon manual manipulation of the receptacle itself into such relation.

41. In a machine of the character described, 125 the combination of a support, an electric motor mounted on said support, an agitator mounted to rotate in a position substantially fixed with respect to the motor, means to automatically retain the receptacle 130

in its cooperative relation with the agitator upon manual manipulation of the receptacle itself into such relation, and means to automatically control the operation of the 5 motor so it will run while the receptacle is held by the retaining means.

42. In a machine of the character described, the combination of a support, an electric motor mounted on said support, an 10 agitator mounted to rotate in a position substantially fixed with respect to the motor, means to automatically retain the receptacle in its cooperative relation with the agitator upon manual manipulation of the receptacle 15 itself into such relation, and means to automatically control the operation of the motor so it will commence to run before the receptacle reaches its operative position and will continue to run while the receptacle is retained in such position.

43. In a machine of the character described, the combination of a support, an electric motor mounted on said support, an agitator mounted to rotate in a position substantially fixed with respect to the motor, means to automatically retain the receptacle in its cooperative relation with the agitator upon manual manipulation of the receptacle 25 itself into such relation, and means to automatically control the operation of the motor so it will run while the receptacle is held by the retaining means, and will continue to run for a limited period during the withdrawal of the receptacle from said retaining 30 means.

44. In a machine of the character described, the combination of a support, an electric motor mounted on said support, an agitator mounted to rotate in a position substantially fixed with respect to the motor, and means to automatically retain the receptacle in its cooperative relation with the agitator upon manual manipulation of the receptacle 40 itself into such relation, comprising a hook to hold the upper portion of the receptacle.

45. In a machine of the character described, the combination with an agitator, a motor for driving the agitator and a receptacle of means for removably supporting the receptacle in its operative position, comprising means for engaging the upper end of the container to hold it laterally and means to support it vertically, and means for controlling the motor operable by placement of the receptacle in the supporting means.

46. In a machine of the character described, the combination with an agitator, a motor for driving the agitator and a receptacle, of means for movably supporting the receptacle in its operative position comprising means for engaging the upper end of the receptacle to hold it laterally and means to underlie the bottom of the receptacle, and means for controlling the motor operable by 65

placement of the receptacle in the supporting means.

47. In a motor driven mixer, the combination with a support, an electric motor mounted at the upper end of said support and having a depending stirring element, a container support below said stirring element, a switch for controlling said motor, and means for actuating said switch upon the placing of a container upon said container support.

48. In a machine of the character described, the combination of a motor, an agitator driven and supported thereby and mounted in fixed relation to the motor, means to stationarily support the motor so there will be sufficient clearance beneath the agitator to permit a receptacle to be manually placed into operative position, and means to removably hold a manually shifted receptacle in a definite operative position so that the agitator will always be eccentric in the receptacle while the latter is supported by said holding means.

49. In a machine of the character described, the combination of a motor, an agitator driven and supported thereby and mounted in fixed relation to the motor, means to stationarily support the motor so there will be sufficient clearance beneath the agitator to permit a receptacle to be manually placed into operative position, and means to removably hold a manually shifted receptacle in eccentric and operative relation to the agitator so the agitator will be adjacent the portion of the receptacle farthest from the receptacle-holding means, to provide greater clearance between the agitator and the holding means.

50. In a machine of the character described, the combination of a support, an electric motor mounted on said support, an agitator mounted to rotate in a position substantially fixed with respect to the motor, means to automatically retain the receptacle in its cooperative relation with the agitator upon manual manipulation of the receptacle itself into such relation, and means operable by the receptacle and independently of the retaining means, for controlling the operation of the motor.

51. In a machine of the character described, the combination of a support, an electric motor mounted on said support, an agitator mounted to rotate in a position substantially fixed with respect to the motor, means to automatically retain the receptacle in its cooperative relation with the agitator upon manual manipulation of the receptacle itself into such relation, and means to automatically control the operation of the motor so it will run while the receptacle is held by the retaining means comprising an element intersecting the path of movement of and shifted by the receptacle.

52. In a machine of the character described, the combination of a hollow column, an electric motor mounted at the upper end of the column, an agitator mounted to rotate in a position substantially fixed with respect to the motor, means to automatically retain the receptacle in its cooperative relation with the agitator upon manual manipulation of the receptacle into such relation, a switch for controlling the motor, and switch operating means comprising a movable member carried by the column and operable by the receptacle.
53. In a machine of the character de-

scribed, the combination of a support, an electric motor mounted on said support, an agitator mounted to rotate in a position substantially fixed with respect to the motor, and means to automatically retain the receptacle in its cooperative relation with the agitator and into which the receptacle can be secured by upward and then lateral manual manipulation of the receptacle itself around the agitator.

Signed at Newark, N. J., this 11th day of February, 1922.

RAYMOND B. GILCHRIST.
